ACETYLENE GENERATOR

Dana Hamilton Bailey, Delavan, Wis., assignor to
 John E. R. Miles, Inc., Minneapolis, Minn., a
 corporation of Wisconsin

Application April 25, 1945, Serial No. 590,276

10 Claims. (Cl. 48—53)

1

This invention relates to an acetylene generator having a novel arrangement for automatically introducing comparatively coarse calcium carbide crystals into a body of water for generating acetylene gas.

One object of the invention is to provide automatic feeding means for the crystals in the form of a simple mechanism operated by the generated gas itself and the amount of operation accurately controlled in accordance with pressure of the gas generated.

Another object is to provide an acetylene generator of this character having various constructional features that insure maximum safety in its operation and safety particularly against explosion.

Still another object is to provide safety features which insure that the residue of calcium hydroxide in the water tank will be discharged and a fresh supply of water introduced each time a new charge of calcium carbide is introduced into the carbide hopper.

With these and other objects in view, my invention consists in the construction, arrangement and combination of the various parts of my device whereby the objects contemplated are attained as hereinafter more fully set forth, pointed out in my claims and illustrated in the accompanying drawings, in which:

Fig. 1 is an elevation of my acetylene generator with portions thereof broken away and other portions in section to show constructional details;

Fig. 2 is an enlarged sectional view on the line 2—2 of Fig. 1, showing the carbide hopper and a feed conveyor for the carbide;

Fig. 3 is an enlarged sectional view on the line 3—3 of Fig. 1, showing a gas operated power means for operating the conveyor, and gas pressure responsive means for automatically controlling the operation of the conveyor driving mechanism;

Fig. 3a is an enlarged sectional view on the line 3a—3a of Fig. 2 showing a cross section of the feed conveyor;

Fig. 4 is a partial side view looking at Fig. 1 from the left;

Fig. 5 is an enlarged sectional view on the line 5—5 of Fig. 4 showing a pressure relief and blow-off valve;

Fig. 6 is an enlarged sectional view on the line 6—6 of Fig. 4, showing a water filling tube;

Fig. 7 is an enlarged sectional view on the line 7—7 of Fig. 4, showing a flush and drain valve;

Fig. 8 is a sectional view on the line 8—8 of Fig.

2

7, showing further details of the flush and drain valve;

Fig. 9 is an enlarged plan view as on the line 9—9 of Fig. 4, showing the relief and blow-off valve;

Fig. 10 is a sectional view on the line 10—10 of Fig. 4, showing carbide hopper details; and

Fig. 11 is a sectional view on the line 11—11 of Fig. 2, showing a plan view of the carbide feed conveyor.

On the accompanying drawings I have used the reference numeral 10 to indicate a main tank for holding a supply of water 12. Within the tank 10 the gas is generated as will hereinafter appear.

15 The tank 10 has an annular seat 14 at its upper end receiving a gasket 16 against which a carbide hopper 18 is seated. The hopper 18 has three brackets 20 as shown in Figs. 1 and 10 welded thereto and clamp plates 22 coact therewith and 20 cooperate with studs 24 welded to the top of the tank 10 for retaining the hopper 18 against the gasket 16 in gas-tight relation to the tank 10. At the top of the hopper 18 a filler plug 26 is provided which may be screw threaded into the hopper with a suitable gasket for sealing purposes.

The lower end of the hopper 18 opens as at 19 into the tank 10 (see Fig. 2) and a cut-off valve 28 is adapted to seat against the end 19 when desired. The cut-off valve 28 is mounted on a valve rod 30 which is pivoted to a crank 32 of a rock shaft 34. The rock shaft 34 is journaled in the top of the hopper 18 and passes out through a gas-tight packing 36 to terminate in a control arm 38. This arm may be normally in the position of Fig. 1 during operation of the gas generator, and when it is desirable to close the valve 28 the arm 38 can be rotated one-half turn clockwise which causes the crank 32 to pull upwardly on the rod 30 and pass dead-center for holding the valve 28 in closed position.

40 Calcium carbide in the hopper 30 is shown at 40. The carbide crystals 40 may be comparatively coarse; for instance, $\frac{1}{4} \times \frac{1}{2}$ of an inch in diameter. For effectively feeding coarse crystals of this character I provide a novel feed conveyor including a pair of pulleys 42 and 44 around which a conveyor belt 46 is trained. The conveyor belt slopes as shown in Fig. 2 so that the carbide crystals 40 can pile up on the belt with a back plate 48 preventing them from rolling off the lower end of the conveyor. The conveyor belt is then driven counterclockwise for feeding the crystals slowly off the upper end of the belt.

45 The pulleys 42 and 44 are supported by a suit-

able framework 50 suspended from the carbide hopper 18. The sides of the framework are sloped to form guide surfaces for the carbide crystals to direct them toward the center of the belt 46.

For automatically driving the conveyor belt 46 I provide a gas operated wheel 52 (see Fig. 3) which is mounted on a shaft 54. The shaft 54 is journaled in a housing 56 which is mounted within another housing 58. The housing 56 is narrower than the housing 58 as shown in Fig. 1, and at the left end of the shaft 54 I provide a chain drive 60 from this shaft to a second shaft 62. The shaft 62 extends out of the housing 58 through a gas-tight packing 64 and is connected to a shaft 66 on which the pulley 44 is mounted. The means of connection is a universal joint in the form of a yoke 68 on the shaft 62 engaging a cross arm 70 of the shaft 66.

A manual means is provided for rotating the shaft 66. This means is in the form of a rod 69 extending through a gas-tight packing 71 of the tank 10 and terminating in a handle 72. The inner end of the rod 69 has a head 74 slotted as at 76 to coact with a cross pin 78 of the shaft 66. The shaft 68 is slidable as well as rotatable in the packing 70.

Returning to the gas operated wheel 52, as shown in Fig. 3, it will be noted that this wheel has a pair of side plates 80 and radial cross plates 82 terminating in circumferentially extending flanges 84. A passageway 86 is provided for conducting gas downwardly through a quantity of water 88 which serves as a seal-off between the interior of the tank 10 and an outlet pipe 90 extending from the top 59 of the housing 58 and communicating with passageway 51. The passageway 86 communicates at its lower end with a gas discharge nozzle 92 arranged in relation to the wheel 52 so that the gas discharges on the right side of a vertical center line through the axis of rotation of the wheel, thus charging with gas the pockets formed by the cross plates 82 and their flanges 84. This tends to rotate the wheel 52 counterclockwise to thereby rotate the shaft 66 also counterclockwise. The gas pockets are indicated at 83 in Fig. 3.

For regulating the rotation of the wheel 52 in an automatic manner I provide a brake pulley 94 on the shaft 66 surrounded by a brake band in the form of an eye 96 formed on a rod 98. The rod 98 extends upwardly through the pipe 90 and terminates in attachment to a diaphragm 100 within a housing formed of a bottom member 102 and a top member 104. These members are suitably bolted together, and within the member 104 a spring 106 is mounted. The spring 106 is adjustable as to tension by means of an adjusting screw 108 to automatically maintain a predetermined gas pressure within the generator as will hereinafter appear.

The housing 102 has an outlet pipe 110 (see Fig. 1) entering a head 112 of a water seal tank 114 which acts as a hydraulic safety valve in case of backfire. The tank 114 has an outlet 116 to a hose which may extend to a welding torch or the like where oxygen is also supplied to the torch for welding operations, or the hose may extend to any device using the gas generated by means of my generator.

Between the pipe 110 and the outlet 116 there is a pipe 118 depending within the tank 114 and terminating in an outlet check valve 120 for further safety against backfire. Perforated baffle plates 122 are mounted within the tank 114 to prevent

any atomized water from passing outwardly through the outlet 116. The outlet is also provided with a shut-off valve 124 when it is desirable to shut-off the gas pressure to the hose connected with the outlet 116.

Referring to Fig. 5, I provide a blow-off and safety valve comprising housing parts 126 and 128 secured together with a diaphragm 130 between them. The diaphragm 130 is normally pressed downward by a spring 132, the tension of which is adjustable by means of a set screw 134. A valve disc 136 is secured to the diaphragm 130 and is normally seated against a seat 138 by the spring 132. The setting of the safety valve may be a desired percentage above the setting of the automatic regulator valve in the housing 102—104.

The housing 126 has an outlet boss 140 with which a blow-off pipe 142 may be connected if it is desirable to discharge the blow-off gas to a remote point such as outside a building in which the generator is installed. The housing 126 is connected to communicate with the interior of the tank 10 through a nipple 144 extending from the tank.

A rock shaft 146 is journaled in the housing portion 128 and has a cam 148 within the housing (see Figs. 5 and 9). This cam is adapted to lift a wire yoke 150 when the rock shaft is rotated clockwise for manually opening the valve 136 for blow-off purposes when recharging the generator. An arm 152 is formed on one end of the rock shaft 146 and has pivoted thereto a safety rod 154 extending upwardly through eyes 156 and 158 and over the top of the filler plug 26. The other end of the rock shaft 146 terminates in an arm 160 and a counterweight 162.

A second safety rod 164 is pivoted to this arm and extends downwardly through an eye 166 on the tank 10 (see Fig. 1). The safety rod 164 has an extension 168 intermediate its height for coacting with a safety latch 170 that is associated with a water filler cap 172. The cap 172 threads on a water intake 174 and a rubber disc 176 is located within the cap 172 and is backed by a metal disc 178. A set screw 180 is provided for the purpose of forcing the disc 176 against the outer end of the filler tube 174 after the cap 172 is screwed onto the tube.

The lower end of the safety rod 164 extends through a guide bracket 182 to a position of co-action with a pivoted arm 184 on a drain valve housing 186. The drain valve housing has a valve seat 188 against which a valve disc 190 is normally seated by screwing a valve stem 192 outwardly to the full line position of Fig. 8. A knob 194 is provided on the stem for this purpose.

The arm 184 is pivoted at 196 to a boss 198 on the valve body 186. It is constrained to move clockwise in Fig. 7 by a spring 200, and a stop pin 202 limits this movement. At the inner or wide open position of the valve 186—190, as shown in Fig. 7 and by dotted lines in Fig. 8, a web 204 of the knob 194 is adapted to swing the arm 184 to the full line position of Fig. 7. When the web 204 is moved away from the arm by unscrewing the valve stem 192 to close the valve disc 190 as shown in full lines in Fig. 8, the spring 200 will rotate the arm clockwise unless the safety rod 164 is in the position of Fig. 8 for a purpose which will hereinafter appear.

Referring to Fig. 1, an agitator plate 206 is mounted on a rock shaft 208 extending out of the tank 10 through a packing 210. The rod 208 terminates in a handle 212 for manual manipulation.

Practical operation:

In the operation of my acetylene gas generator, the tank 10 is filled with the water 12 to the level of the filler tube 174, as shown in Figs. 1 and 6. Considering the hopper 18 filled with calcium carbide and the housing 58 filled with water as well as the safety tank 114 filled with water to the level indicated, the generator may be started in operation by manual means. This is accomplished by pushing the rod 69 inwardly until the slot 76 engages the cross pin 78 and then rotating the handle 72 counterclockwise about one revolution, which results in some of the carbide crystals dropping from the upper end of the conveyor, as shown in Fig. 2, and into the water 12. This results in generation of gas which fills the space in the tank 10 above the water level, displacing air therefrom through the outlet 116.

The pressure of the gas as it is being generated can be observed on a pressure gauge 129 screwed into the safety valve housing 126. The generator is purged of air by leaving the valve 124 open until enough gas has been generated to displace the air. The generated gas, in passing to the outlet 116, first enters the passageway 86 and displaces the water in it, the water merely passing into the housing 58 and remaining there.

The gas, in leaving the passageway 86 through the discharge nozzle 92, enters the gas pockets indicated at 83 in Fig. 3, in the wheel 52. This makes the right side of the wheel lighter than the left side so that the wheel rotates counterclockwise, thus driving the shaft 66 counterclockwise through the chain drive 60. Thus, after the beginning of the generation of gas caused by manual manipulation of the handle 72, further carbide is automatically fed to the water by rotation of the shaft 66 causing the conveyor belt 46 to travel counterclockwise.

When the gas pressure has increased to the setting of the spring 106 it will have raised the diaphragm 100 to a position where the hook 96 of the rod 98 will frictionally engage the lower side of the pulley 94 on the shaft 62, thus stopping its rotation. Any gas generated thereafter merely passes upwardly around the wheel 52 into the housing 56 and then through the opening 57 in the top of this housing and into the pipe 90 without rotating the wheel 52. There is of course enough clearance between the wheel and the housing 56 to permit free passage of the gas in this manner. Thus the pressure of the gas is automatically maintained.

The gas passes from the housing 102 of the pressure regulating valve through the pipes 110 and 118 and through the check valve 120 into the safety tank 114. It bubbles up through the water therein and passes through the perforated baffle plates 122 to the outlet 116 and from there to the welding torch or whatever mechanism is being operated by the gas.

In the event that excessive gas pressure is generated the pressure will raise the diaphragm 130 (see Fig. 5) and the valve disc 136 from its seat 138, thus permitting blow-off of the excess through the pipe 142. The spring 132 is set at a somewhat higher setting than the spring 106 so that normally the gas pressure regulating valve of Fig. 3 is the automatic control means, whereas the blow-off valve of Fig. 5 is a safety means in case too much carbide is discharged from the conveyor 46 by the operation of the wheel 52.

After a hopper of carbide has been exhausted and the hopper has to be recharged, it is desirable to drain off the water 12 from the tank 10 and the calcium hydroxide therein formed by the calcium carbide as it generates acetylene gas. If the water and calcium hydroxide are not drained and another hopper of calcium carbide is used with the same water, there is danger of an explosion because of too much carbide in proportion to the supply of water.

The dimensions of the tank 10 and the hopper 18 are so related that one hopper of carbide used with one tank of water is safe, but to insure that the water is drained out every time a fresh hopper of carbide is used I provide a safety arrangement including the safety rods 154 and 164, the operation of which will now be described.

Before removing the filler plug 26 from the top of the carbide hopper it is desirable to relieve the gas pressure in the generator. This is accomplished by opening the valve 136 of Fig. 5 by lifting the weight 162. This rotates the cam 148 clockwise to lift the left side of the valve disc from the seat 138 and thereby permits blow-off of the excess pressure. At the same time the rod 154 is pulled downwardly as to the dotted position in Fig. 1 so as to permit access to the filler plug 26 for removing it. Thus I insure that the excess pressure is blown off before the filler plug 26 is removed, otherwise the excess pressure would blow the lid off when it is almost unscrewed and be dangerous to the operator.

Lifting the weight 162 also pulls the safety rod 164 upwardly, which causes the extension 168 thereof to be raised above the catch 170, and the catch drops down to a position against the upper edge of the filler cap 172. At the same time the lower end of the rod 164 is pulled upwardly from in front of the lever 184 so that the spring 200 (see Fig. 7) will swing the lever to the dotted line position. It is now impossible to push the rod 164 downwardly again to its original position by lowering the weight 162, thus indicating to the operator, after he fills the carbide hopper, that there is a further operation to be performed, to wit: the draining and flushing of the tank 10.

The downward movement of the safety rod 164 is prevented by its location above the right-hand end of the lever 184 in the dotted position of Fig. 7. In order to return the lever 184 to the full line position of Fig. 7 so that the rod 164 can move downwardly, the knob 194 must be rotated to its inner limit of movement as shown by solid lines in Fig. 7 and dotted lines in Fig. 8. During the last revolution of this movement the web 204 engages the left end of the lever 184 for swinging it from the dotted position to the full line position, thereby permitting the tank to be drained through the wide open valve 190. During the draining operation the handle 212 may be manipulated for agitating the water and calcium hydroxide to effect a complete draining operation.

Since the tank is now drained it will be necessary to fill it again with water and to do this the set screw 180 is loosened for backing the rubber disc 176 off the end of the filler tube 174 without causing it to rotate thereon, and thus be damaged by such rotation. As soon as the disc is off the filler tube, the cap 172 may be removed as shown in Fig. 6, which will permit the latch 170 to drop down to a position that prevents the filler cap from being put on again until the latch is raised to the position of Fig. 1 and the weight 162 lowered to hold the latch in this position.

It is desirable at this time to flush out the tank by pouring in water and letting it drain out through the drain valve 186, or by means of a hose. The safety rods 154 and 164 are now back in their full line positions of Fig. 1 and accordingly the drain valve may be closed, the tank 10 filled with water, and the filler cap 172 replaced. The set screw 180 is then tightened for sealing the filler tube, and the generator is in condition for starting operation by manipulation of the handle 12, as already described. A guard flange 169 in front of the rod 168, and the size of the cap 172, prevent ready access to the latch 170 to return it to the position of Fig. 1. This insures that the cap will have to be removed and will serve as a reminder to the operator to replenish the water supply whenever he refills the carbide hopper.

From the foregoing specification it will be obvious that I have provided an automatic means for feeding carbide crystals which are comparatively coarse. Carbide of this character is preferable to finer carbide which has carbide dust in it, and by the use of a conveyor belt arrangement the comparatively coarse carbide crystals are efficiently fed to the water. The means for accomplishing the automatic feeding is operated by the gas pressure itself and therefore requires no outside source of power. The operation is entirely automatic in response to the pressure of the gas generated so that any increase in pressure above a predetermined degree prevents further feeding until such time as the pressure drops below that degree.

Provision has been made for safely operating the generator by requiring that the recharging operations be performed in proper sequence, the safety mechanism being arranged so as to preclude any possibility of the operator forgetting or neglecting to provide a fresh charge of water for each fresh charge of carbide.

Although I have herein shown and described a preferred embodiment of my invention, manifestly it is capable of modification and rearrangement of parts without departing from the spirit and scope thereof. I do not, therefore, wish to be understood as limiting this invention to the precise form herein disclosed, except as I may be so limited by the appended claims.

I claim as my invention:

1. In an acetylene generator, a tank for water, a hopper mounted thereon for carbide, means for feeding carbide from said hopper to said tank in accordance with the pressure of the gas generated in the said tank, a blow-off valve for said tank, a drain valve for said tank, a lever pivoted to the drain valve and spring biased to one position, a safety rod preventing movement of said lever due to its spring bias, said safety rod being connected with said blow-off valve for preventing closing of the blow-off valve except when said drain valve has been moved to an open position, said drain valve when in said position engaging said lever to move it against its bias to thereby permit movement of said safety rod by closure of said blow-off valve.

2. In an acetylene generator, a tank for water, a hopper thereabove for carbide, means for automatically feeding carbide from said hopper to said tank, a blow-off valve for said tank, a filler plug for said hopper, means for preventing removal of said filler plug when said blow-off valve is closed, a drain valve for said tank, a lever pivoted thereto and spring biased to one position, a safety rod preventing movement of said lever due

to its spring bias, said safety rod being connected with said blow-off valve for preventing closing of the blow-off valve except when said drain valve has been moved to an open position, said drain valve when in said position engaging said lever to move it against its bias to thereby permit movement of said safety rod by closure of said blow-off valve.

3. In an acetylene generator, a water tank, a hopper thereabove for carbide, means for automatically feeding carbide to said tank comprising a carbide feed mechanism adjacent the bottom of the hopper to receive carbide therefrom, a motor for operating said feed mechanism driven by acetylene gas formed in said tank, a container for said motor, said motor being positioned adjacent the bottom of said container, a conduit for acetylene gas connected between the top of said tank and the bottom of said container to feed gas to said motor, said inlet conduit and said container being filled with water, an outlet conduit for acetylene gas from the top of said container, a backfire chamber connecting at its top with said outlet conduit and having a vertical standpipe for conveying said acetylene gas to the bottom thereof, an outlet for acetylene gas from the bottom of said standpipe, an outlet for acetylene gas from the top of said chamber and a passageway formed by the chamber to convey gas from the bottom of said standpipe to the outlet at the top of said chamber, said chamber being filled with water to a level to cover the gas outlet at the bottom of the standpipe.

4. The apparatus claimed in claim 3 wherein 35 baffles are provided in the backfire chamber to prevent the water therein from entering the outlet therefrom.

5. In an acetylene generator, a water tank, a hopper thereover for carbide, means for automatically feeding carbide from said hopper to 40 said tank comprising a carbide feed mechanism adjacent the bottom of said hopper to receive carbide therefrom, a motor for operating said feed mechanism driven by acetylene gas formed in said tank, a container for said motor, said motor being disposed adjacent the bottom of said container, a second container surrounding said motor container and having a passageway therein for conveying acetylene gas from said tank to said motor, an opening in the bottom of said 45 motor container affording passage of said acetylene gas into the motor, both of said containers being filled with water, an acetylene gas outlet from the top of said motor container, and a conduit connecting with said outlet for conveying acetylene gas from said tank.

6. In an acetylene generator, a water tank, a hopper thereover for carbide, means for automatically feeding carbide from said hopper to 50 said tank comprising a carbide feed mechanism adjacent the bottom of said hopper to receive carbide therefrom, a motor for operating said feed mechanism driven by acetylene gas formed in said tank, a container for said motor, said motor being disposed adjacent the bottom of said container, a second container surrounding said motor container and having a passageway therein for conveying acetylene gas from said tank to 55 said motor, an opening in the bottom of said motor container affording passage of said acetylene gas into the motor, both of said containers being filled with water, an acetylene gas outlet from the top of said motor container, a conduit connecting with said outlet for conveying acetylene gas from said tank, and an acetylene gas op-

erated brake for said motor including a diaphragm in communication with said outlet conduit.

7. In an acetylene generator, a tank for water having an inlet for adding water thereto, a removable closure for said inlet, a latch operable in one position for preventing disposal of said closure in closing position on said inlet and operable in another position to permit such disposal of said closure, a hopper mounted on said tank for carbide, means for feeding carbide from said hopper to said tank in accordance with the pressure of the gas generated in said tank, a blow-off valve for said tank, means operable by closure of said blow-off valve for holding said latch in a position permitting disposal of said closure on said inlet, a drain valve for said tank, a lever pivoted thereto and spring biased to one position, and a safety rod preventing movement of said lever due to its spring bias, said safety rod being connected with said blow-off valve for preventing closing of the blow-off valve except when said drain valve has been moved to an open position, said drain valve when in said position engaging said lever to move it against its bias to thereby permit movement of said safety rod by closure of said blow-off valve.

8. In an acetylene generator, a tank for water having an inlet for adding water thereto, a hopper mounted on said tank for carbide, means for feeding carbide from said hopper to said tank in accordance with the pressure of the gas generated in said tank, a blow-off valve for said tank, a drain valve for said tank, a lever pivoted thereto and spring biased to one position, a safety rod preventing movement of said lever due to its spring bias, said safety rod being connected with said blow-off valve for preventing closing of the blow-off valve except when said drain valve has been moved to an open position, said drain valve when in said position engaging said lever to move it against its bias to thereby permit movement of said safety rod by closure of said blow-off valve, a removable closure for said inlet, a latch operable in one position for preventing disposal of said closure in closing position on said inlet and operable in another position to permit such disposal of said closure, and means operable by closure of said blow-off valve for holding said latch in a position permitting disposal of said closure on said inlet.

9. In an acetylene generator, a tank for water having an inlet for adding water thereto, a hopper mounted on said tank for carbide, means for feeding carbide from said hopper to said tank in accordance with the pressure of the gas generated in said tank, a blow-off valve for said tank, a drain valve for said tank, a lever pivoted thereto and spring biased to one position, a safety rod preventing movement of said lever due to its spring bias, said safety rod being connected with said blow-off valve for preventing closing of the

blow-off valve except when said drain valve has been moved to an open position, said drain valve when in said position engaging said lever to move it against its bias to thereby permit movement of said safety rod by closure of said blow-off valve, a removable closure for said inlet, a latch operable in one position for preventing disposal of said closure in closing position on said inlet and operable in another position to permit such disposal of said closure, and means operable by closure of said blow-off valve for holding said latch in a position permitting disposal of said closure on said inlet.

10. In an acetylene generator, a tank for water; a hopper mounted thereon for carbide; means for feeding carbide to said tank; a combination manual blow-off and automatic safety valve for said tank; a drain valve for said tank; a closure for said inlet; a carbide filler plug for said hopper; a lever for manually venting said blow-off valve, and a single leverage system including said lever, means operative in one position to block removal of the carbide filler plug before the blow-off valve is manually vented but operative in another position to permit such removal after manual venting of said blow-off valve, means operative in one position to block reclosure of said blow-off valve before said drain valve has been moved to open position but operative in another position to permit such reclosure after said drain valve has been moved to open position, and means operative in one position to block replacing of said water inlet closure after removal thereof before manual closing of said blow-off valve but operative in another position to permit replacing of said water inlet closure after manual closing of said blow-off valve, said leverage system being actuated by manual movement of said lever to insure venting of said generator before addition of carbide, draining of said generator before gas generation is resumed after addition of carbide, and addition of water to said generator after draining thereof.

DANA HAMILTON BAILEY.
